EGG CLEANING DEVICE

Russell C. Storer, Cleveland, Ohio

Application January 24, 1938, Serial No. 186,515

5 Claims. (Cl. 15—93)

This invention relates to cleaning eggs and more particularly to an improved device for rapidly and effectively removing dirt, stains, etc. from the surface of the egg shell. Numerous machines have been devised for cleaning eggs. Frequently such devices have contemplated washing of the eggs with water. Certain difficulties arise, however, when water is used as a cleaning agent for eggs which are to be placed in cold storage because of the absorption of the water by the egg shell and later resulting discoloration or mold due to such water absorption.

It is among the objects of my invention to provide a dry cleaning device for eggs which is simple and economical both in construction and upkeep and which operates rapidly and effectively to remove undesired material from the shell without damage to the egg or danger of subsequent difficulties when the egg is placed in storage. Another object of my invention is the provision of an egg cleaning device the cleaning agent of which will last for a long time and need be replaced only at long intervals and in which such replacement can be effected quickly and easily.

The above and other objects of my invention will appear from the following description of several embodiments of my invention, reference being had to the accompanying drawing, in which—

Figure 1 is a vertical cross-sectional view through one form of my egg cleaning device.

Figure 2 is a fragmentary vertical cross-sectional view of a modified form of cleaning device.

Referring now particularly to Figure 1, the egg 1 is held in the hand 2 of the operator and the spot on the egg which is to be cleaned is held against the surface 3 of the mass 4 of steel wool or the like which is retained within the cylindrical housing 5. The housing 5 is provided with a nose piece 6 which preferably tapers to the restricted opening 7 in order to retain the steel wool 4 in the housing but at the same time permitting it to be automatically fed through the opening to provide at all times a self renewing cleaning surface 3. A freely movable, floating disc plunger member 8 is adapted to slide freely in the housing 5 and engages the rear surface of the mass 4 of steel wool and a coil spring 9 lies between the disc 8 and the end plate 10. As the spring 9 is maintained under compression it at all times exerts a force tending to force the steel wool 4 out of the opening 7, thus providing an automatic feed of the steel wool as it may be

worn away on the surface 3. In order to maintain the spring 9 in its centered position an annular flange 11 may be provided on the inner surface of the end plate 10.

Due to the tapering shape of the nose piece 6 the mass of wool 4 may be fed forwardly through the restricted opening 7, but it will be held back sufficiently to prevent undesired extrusion of the wool. When it is exhausted, or when the plunger 8 reaches a point where it cannot advance further due to the reduction in diameter of the nose piece 6, the housing or can 5 may be detached from the end piece 10 with which it has threaded engagement and additional steel wool inserted therein. The parts will then be reassembled as shown in Figure 1 and the device will be ready to function for another relatively long period of time.

A coupling member 12 is secured to the end plate 10, as by screws 13, and is held on the motor shaft 14 by a set screw 15. The motor 16 may be of any suitable type and may be mounted as desired, for example, on the bench where the eggs are being sorted and classified.

In the modified form of my cleaning device shown in Figure 2, the housing 17 is provided with a steel wool retaining end member 18 and the plunger disc 19 is of a convex form. The spring 20 serves the same function as the spring 9 and in Figure 2 an annular flange 21 has been provided on the plunger disc 19 to retain the spring 20 in position. It will be understood that the housing 17 may be directly supported on a motor shaft, as shown in Figure 1, or may be rotatably mounted in any other desired manner.

The steel wool in the embodiment shown in Figure 2 is made up in disc shaped bats 22, the end bat 22^a assuming a convex surface shape which projects out from the end piece 18 facilitating the egg cleaning operation. This convex form is preferably maintained to a certain degree in all of the bats 22 by the convex form of the plunger disc 19.

In the operation of the device the entire housing 5 is rapidly rotated and the egg held against the projecting surface of the fine steel wool. Although I prefer that the surface of the steel wool be convex in form so that it projects out beyond the end pieces 6 and 18 in order that the possibility of striking the egg against the housing 50 will be reduced, it will be understood that my device will be operative to clean eggs effectively even though the surface of the steel wool be perfectly flat. The rapidly rotating steel wool quickly removes dirt from the surface of the egg 55

- and, as the egg and wool are dry, centrifugal force due to the rotation will throw off the removed dirt and prevent clogging of the steel wool mass. The open porous nature of the mass of steel wool facilitates this self cleaning action and the spongy structure of the mass of steel wool gives a springy, resilient surface against which the egg may be held without danger of cracking or excessive abrasion at any one point on the surface of the egg.
- In the embodiment shown in Figure 2, after the end bat 22^a becomes worn sufficiently it can be completely removed by pulling it out through the hole in the opening in the end piece 18 and when this is done an entire new working surface on the next bat 22 immediately therebehind will be promptly forced up to operating position at the opening by the action of the spring 20 against the convex plunger disc 19.
- It will be observed that my egg cleaning device is extremely simple, contains a minimum of parts, may be economically manufactured and will remain in operation for long periods of time without attention. Although I have described in considerable detail the illustrated embodiments of my invention, it will be understood by those skilled in the art that variations and modifications may be made in the apparatus employed without departing from the spirit of my invention. I do not, therefore, wish to be limited to the specific devices herein illustrated and described but claim as my invention all embodiments thereof coming within the scope of the appended claims.

I claim:

1. An egg cleaning device of the type described, including a housing having a restricted opening at one end, a mass of steel wool in said housing and projecting out through said opening, a freely movable plunger member adapted to engage the steel wool in the housing, spring means for continuously exerting a force against said plunger tending to push said steel wool out through said opening and means, coaxially arranged with respect to said housing and said restricted opening, for rotating said housing.

2. In an egg cleaning device of the class described, a generally cylindrical housing having a tapering end portion and an opening in said end portion of smaller diameter than the diameter of said housing, a mass of steel wool in said housing, and independent spring means for continuously exerting a force against said steel wool in said housing tending to push said steel wool toward said smaller diameter opening in said housing, said tapering end portion being adapted to oppose the force exerted against said wool by said independent spring means.

3. In an egg cleaning device of the class described, a generally cylindrical housing having a tapering end portion and an opening in said end portion of smaller diameter than the diameter of said housing, a mass of steel wool in said housing, independent spring means for continuously exerting a force against said steel wool in said housing tending to push said steel wool toward said smaller diameter opening in said housing, said tapering end portion being adapted to oppose the force exerted against said wool by said independent spring means and means, coaxially arranged with respect to said housing and said opening, for rotating said housing.

4. In an egg cleaning device, a housing having a restricted opening at one end, a plurality of disc shaped bats of steel wool disposed in said housing, a plunger member having a convex surface, said surface engaging the steel wool bat most remote from said opening, and spring means tending to push said plunger disc toward said opening.

5. In an egg cleaning device, a housing having a restricted opening at one end, a plurality of disc shaped bats of steel wool disposed in said housing, a plunger member having a convex surface, said surface engaging the steel wool bat most remote from said opening, spring means tending to push said plunger disc toward said opening, and means for rotating said housing.
